ROCK BIT

**Alfred C. Catland, Alhambra, Calif., assignor to
Globe Oil Tools Company, Los Nietos, Calif., a
corporation of California.**

Application February 18, 1938, Serial No. 191,243

1 Claim. (Cl. 308—198)

This invention relates to a well drilling tool and relates more particularly to a rock bit for use in the rotary method of well drilling. A general object of this invention is to provide a practical dependable rock bit embodying improved anti-friction bearing means for the roller cutters.

Another object of this invention is to provide a rock bit embodying simplified and inexpensive anti-friction bearings for the cutters.

Another object of this invention is to provide a rock bit in which a single bearing member is provided for each cutter and rows of balls cooperate with grooves in the cutters and their respective bearing members to support the cutters against both radial thrusts and axial thrusts in both directions. The cutter supporting bearing means of the present invention employing a single bearing member for each cutter is simple and easy to manufacture and assemble.

Another object of this invention is to provide a rock bit of the character mentioned in which the single bearing member of a cutter mounting means may directly engage against legs or wings 25 of the bit body or against a body part and the bearing member of an adjacent cutter, depending upon the position of the cutter, without the necessity of employing thrust washers, spacers or other similar parts.

30 Another object of this invention is to provide a rock bit of the character mentioned in which the bearing members do not have transverse seams, cracks or lines of division that wear or admit particles of solid matter or that allow end play of the bearing parts.

Another object of this invention is to provide a rock bit of the character mentioned in which the single bearing members of the respective cutters are integral except for plugs that occupy the ball admitting openings and, being integral, are simple to machine and assemble.

Another object of this invention is to provide a rock bit construction of the character mentioned embodying novel and dependable means for retaining the above-mentioned plugs in the desired position in their openings so that they cannot become displaced or cause jamming of the balls.

50 A further object of this invention is to provide cutter mounting means for the cutters of a well bit in which the balls have extensive cooperation with the cutters and their bearing members, reducing the intensity of the pressures or forces on the balls and their races and materially reducing 55 the wear.

The various objects and features of my invention will be fully understood from the following detailed description of a typical preferred form and application of my invention, throughout which description reference is made to the accompanying drawings in which:

Fig. 1 is a side elevation of a rock bit embodying the features of the present invention with the lower portion broken away to illustrate the outer cutters and bearing means and the adjacent body parts in vertical cross section. Fig. 2 is an enlarged top elevation of the bearing member for one of the outer cutters removed from the bit. Fig. 3 is a transverse sectional view taken as indicated by line 3-3 on Fig. 2. Fig. 4 is an enlarged top view of one of the plugs employed in the bearing member of an outer cutter. Fig. 5 is a longitudinal sectional view of the plug shown in Fig. 4. Fig. 6 is a longitudinal sectional view of the same plug taken in a plane of sectioning at 90° to that of Fig. 5. Fig. 7 is a side elevation of the bit with the lower portion broken away to illustrate the inner cutter, their bearing means and the adjacent body parts in vertical cross section. Fig. 8 is an enlarged longitudinal sectional view of one of the large inner cutters on its bearing showing the bearing elements in elevation and Fig. 9 is a view similar to Fig. 8 showing one of the small inner cutters in cross section and arranged on its bearing. 30

The improved rock bit of the present invention includes, generally, a body 10, outer cutters 11, bearing means 12 for rotatably mounting the outer cutters 11 on the body 10, sets of inner cutters 13 and 14 and bearing means 15 for rotatably mounting the inner cutters 13 and 14 on the body 10.

The bit body 10 is adapted to be connected with the lower end of a rotary well drilling string. In the particular case illustrated in the drawings a tapered screw-threaded pin 16 is provided on the upper end of the body 10 to facilitate its connection with the drilling string. The body 10 is provided with depending parts to support the cutter mounting means 12 and 15. A substantially central web 17 projects from the lower end of the body 10. The web 17 is broadened adjacent its lower end to have two downwardly and outwardly inclined wings 18. Two diametrically opposite legs 19 project downwardly and outwardly from the lower end of the body 10. The legs 19 are spaced outwardly from the wings 18 and the inner sides 20 of the legs 19 are parallel with the opposing outer surfaces 21 of the wings 18. The inner sides 20 of the legs 19 and

the outer surfaces 21 of the wings 18 are flat and are inclined downwardly and outwardly with respect to the vertical axis of the body 10.

The body 10 is further provided with two diametrically opposite legs 22 projecting from its lower end. The legs 22 are spaced substantially 90° from the legs 19 and their lower portions are substantially vertical. The web 17 with its wings 18 and the legs 19 and 22 are preferably integral parts of the body 10. It is to be understood that the body 10 is provided with the usual circulation passages and discharge ports for the circulation fluid employed in the rotary method of well drilling.

15 The outer cutters 11 are provided to act on the outer portion of the bottom wall of the well and to cut the well bore to gauge. The cutters 11 are in the nature of toothed roller cutters and there are two cutters 11, one being mounted between each set or pair of adjacent wings and legs 18 and 19. The outer cutters 11 are frusto-conical, having pitched or inclined peripheries and flat opposite ends. A central longitudinal opening 23 extends through each cutter 11. The peripheries of the cutters 11 are provided with suitable cutting teeth 24. The ends or corners of the teeth 24 at the large ends of the frusto-conical cutters 11 are cut away or bevelled off at 25 to act on the side wall of the well bore as will be subsequently described.

In accordance with the invention annular ball races or grooves are provided in the interior of each cutter 11. In the preferred construction illustrated in the drawings two axially spaced annular grooves 26 and 27 are provided in the wall of each cutter opening 23. The grooves 27 are provided in the base end portions or the large end portions of the frusto-conical cutters 11 and may be somewhat larger in diameter than the grooves 26. An annular recess or socket 28 is preferably provided in the outer or large end of each cutter 11 in concentric relation with its opening 23.

The bearing means 12 for rotatably supporting the outer cutters 11 are in the nature of anti-friction ball bearings. As the two bearing means 12 may be identical, I will proceed with a detailed description of one bearing means 12, it being understood that such description is equally applicable to the other bearing means 12.

The bearing means 12 includes a race or bearing member 29. The bearing member 29 is a generally cylindrical spool-like member adapted to be received in the opening 23 of a cutter 11. The member 29 is provided with a central longitudinal opening 30 extending through it from one end to the other. The opposite ends of the bearing member 29 are flat and are adapted to cooperate with the opposing surfaces 20 and 21 of the adjacent body leg 19 and wing 18. An annular radial flange 31 is provided at the outer end of the bearing member 29 and is partially received in the socket 28 of the cutter 11 to assist in preventing the entrance of cuttings and particles of solid matter to the cutter opening 23. The periphery of the bearing member 29 is provided with two spaced annular ball grooves 32 and 33. The groove 32 directly opposes the groove 26, while the groove 33 directly opposes the groove 27. The sets or pairs of grooves 26 and 32 and 27 and 33 are of substantial depth, as illustrated throughout the drawings.

The bearing means 12 further includes balls 34 occupying or cooperating with the pairs of opposing or registering grooves 26 and 32 and 27

and 33. The balls 34 rotatably support the cutter 11 on the bearing member 12 with a minimum of friction. Because of the substantial depths of the grooves 26 and 32 and 27 and 33 the balls 34 are operable to assume the end thrusts in 5 both directions as well as the radial thrusts and therefore may constitute the sole means for rotatably supporting the cutters 11. Accordingly, the ends of the cutters 11 need not bear on thrust washers or thrust surfaces of the body 10. 10 The sets or pairs of opposing grooves 26 and 32 and 27 and 33 are related so that the balls 34 have extensive cooperation with the grooves for the transmission of axial thrusts both inwardly and outwardly with respect to the central vertical 15 axis of the bit.

The bearing member 29 is provided with a radial opening 35 extending from the bottom or wall of the groove 32 to the opening 30 and a similar radial opening 36 extending inwardly 20 from the bottom or wall of the groove 33 to the opening 30. The openings 35 and 36 may be simple cylindrical bores and are sufficiently large in diameter to receive or pass the balls 34. The openings 35 and 36 provide for the easy insertion 25 or arrangement of the balls 34 in the pairs of opposing grooves 26 and 32 and 27 and 33, respectively. Following the arrangement of the bearing member 29 in the opening 23 of the cutter 11 the balls 34 are passed outwardly through the 30 openings 35 and 36 to the opposing grooves 26 and 32 and 27 and 33 to occupy the same and thus rotatably support the cutters on the bearing member.

The invention provides simple and dependable 35 means for retaining the balls 34 in the pairs of opposing grooves 26 and 32 and 27 and 33. This means includes a plug 37 for occupying the opening 35 and a similar plug 38 for occupying the opening 36. The plugs 37 and 38 are arranged 40 in their respective openings 35 and 36 following the arrangement of the balls 34 in the opposing grooves as just described and their outer ends are shaped to constitute flush continuations or portions of the walls of the grooves 32 and 33, respectively. A transverse groove or notch 39 is provided in the outer end of the plug 37 and a similar groove or notch 40 is provided in the outer end of the plug 38. The notches 39 and 40 are formed so that their walls constitute flush 50 continuations of the grooves 32 and 33, respectively. The openings 35 and 36 are preferably in the upper part of the bearing member 29 so that the plugs 37 and 38 are not subjected to the heavy forces transmitted between the cutter 11 55 and the member.

The invention provides dependable means for holding the plugs 37 and 38 against outward movement and against turning so that the walls of their notches 39 and 40 remain in flush relation with the walls of the grooves 32 and 33. This means includes a groove or keyway 41 in the wall of the opening 30 and ears or keys 42 and 43 on the plugs 37 and 38, respectively, for co-operating with the keyway 41. The keyway 41 65 may extend between the opposite ends of the opening 30 and intersects the openings 35 and 36. The keys 42 and 43 are in the nature of lugs or ears projecting radially from diametrically opposite sides of the plugs 37 and 38, respectively. 70 The keyway 41 may be flat-walled or rectangular in cross section and the keys 42 and 43 may be correspondingly shaped to fit the keyway. The keys 42 and 43 are preferably integral with their respective plugs 37 and 38 as illustrated in the 75

- drawings, although it is obvious that they may be separately formed parts suitably fixed to the plugs if desired. It is believed that it will be apparent how the cooperation of the keys 42 and 43 with the keyway 41 holds the plugs 37 and 38 against turning and against outward movement so that the notches 39 and 40 remain in flush relation with the walls of the grooves 32 and 33 respectively.
- 10 Following the assembly of the bearing member 29 in the cutter opening 23, the arrangement of the balls 34 in the sets of registering grooves 26 and 32 and 27 and 33 and the placing of the plugs 37 and 38 in their respective openings 35 and 36, the assembly of the cutters 11 and their bearing elements is inserted between a leg 19 and a wing 18. As described above the outer end of the bearing member 29 may engage the inner side 20 of the leg 19 and the inner end of the bearing member may engage the surface 21 of the wing 18. It is preferred to provide a lug 45 on the outer end of the bearing member 29 to engage upwardly against the lower end of the leg 19 for the direct transmission of forces between the bearing member 29 and the bearing member and the body wing. It may be desired to weld the lug 45 to the leg 19 at 47 to assist in securing the bearing member 29 to the body.
- The means 12 for mounting the outer cutters 11 further includes a supporting member or pin 48. A downwardly and inwardly inclined opening 49 is provided in the wing 18 and a downwardly and inwardly inclined opening 50 is provided in the leg 19 to be in axial alignment with the opening 49. The opening 30 in the bearing member 29 is in registration with the openings 49 and 50 when the assembly of the cutter 11 and its bearing elements is in place between the wing 18 and the leg 19. The supporting pin 48 is passed outwardly through the opening 49 and the opening 30 and has its outer end portion threaded in the opening 50. A head 51 on the inner end of the pin 48 cooperates with the wing 18. The head 51 may be counter-sunk or recessed in the inner side of the wing 18. The outer part of the pin 48 may be distorted or peened over at 52 to lock the pin against unthreading. The pin 48 cooperates with the plugs 37 and 38 to hold the plugs against inward movement. The pin 48 may be tightened down so that the ends of the bearing member 29 are tightly held between the inner side 20 of the leg 19 and the surface 21 of the wing 18 so that there is no end play or movement in the bearing member and the cutter assembly.
- 60 The outer cutters 11 rotatably supported on the body 10 as described above, are rotatable about downwardly and inwardly inclined axes and project downwardly beyond the lower ends of the wings 18 and the legs 19 to act on the bottom wall of the well bore and project outwardly beyond the legs 19 so that the bevelled-off corners 25 of their teeth 24 may act on the side wall of the bore. It will be understood how the outer cutters 11 make an annular cut in the earth formation to cut the well bore to gauge.
- The inner cutters 13 and 14 are provided in sets, there being two sets of inner cutters each including a cutter 13 and a cutter 14. The cutters 13 are arranged at the inner sides of the legs 22 to act within and in overlapping relation to
- the path of travel of the cutters 11 and the cutters 14 are located at the opposite sides of the web 17 to act on the inner or central portion of the well bore. The cutters 13 and 14 are roller cutters, the cutter 13 being frusto-conical and the cutter 14 being cylindrical. Suitable cutting teeth 53 are provided on the inclined or pitched peripheries of the cutters 13 and suitable teeth 54 are provided on the peripheries of the cutters 14. The frusto-conical cutters 13 are arranged so that their small ends are larger in diameter than the cylindrical cutters 14.
- Central longitudinal openings 55 extend through the cutters 13 and concentric recesses or sockets 56 are provided in the large ends of the cutters 13. Spaced annular ball grooves 57 and 58 are provided in the walls of the cutter openings 55. The grooves 57 and 58 are of substantial depth and the grooves 58 in the outer end portions of the cutters face axially outward as well as inwardly toward the central longitudinal axes of the cutters. The cutters 14 are provided with central longitudinal openings 59. There are two spaced annular ball grooves 60 and 61 in the wall of each cutter opening 59. In the preferred construction the body web 17 is provided adjacent its lower end with cylindrical bosses 62 projecting outwardly toward the legs 22. The openings 59 in the cutters 14 are proportioned to receive the bosses 62 with suitable clearance.
- The bearing means 15 for rotatably mounting the inner cutters on the body 10 comprises a single bearing member 63 for each cutter 13, a single bearing member 64 for each cutter 14 and a single support member 65 carried by the body web 17 and the legs 22 and supporting the members 63 and 64.
- The bearing members 63 for the cutters 13 are generally cylindrical spool-like parts having central longitudinal openings 66. The outer ends of the members 63 are adapted to cooperate with the inner sides of the body legs 22 and the inner ends of the members 63 are engaged by the members 64 as will be subsequently described. Annular radial flanges 67 are provided on the members 63 at their outer ends and are received in the sockets 56 with suitable clearance. The members 63 are received in the openings 55 of the cutters 13 with clearance and the flanges 67 received in the sockets 56 serve to prevent the entrance of large particles of solid matter to the openings. Each member 63 has two longitudinally spaced ball grooves 68 and 69. The grooves 68 oppose or register with the grooves 57 and the grooves 58 oppose or register with the grooves 59. In the preferred construction a lug 70 is provided on the outer end of each member 63 and cooperates with the lower end of a body leg 22 to prevent rotation of the member and to transmit forces between the body leg 22 and the bearing member.
- The bearing means or cutter mounting means 15 further includes series of balls 71 occupying or cooperating with the sets of registering grooves 57 and 68 and 58 and 69. The balls 71 rotatably support the cutters 13 on the bearing members 63 for free rotation. The grooves 57 and 68 and 58 and 69 are proportioned and related to substantially entirely receive the balls 71 so that the balls are operable to transmit axial thrusts in both directions as well as the radial thrusts and thereby constitute the sole means for rotatably supporting the cutters 13. The grooves 58 and 69 are faced and related so that the balls 71 cooperating with them dependably transmit the

outward end thrusts imposed on the cutters 13. The cutters 13 being supported entirely by the balls 71 do not bear on the members 63 and need not bear on the flanges 67 or the body legs 22.

5 The members 63 are provided with radial openings 72 extending outwardly from their openings 66 to the grooves 68 and have similar openings 73 extending outwardly from their openings 66 to the grooves 69. The openings 72 and 73 are 10 proportioned to admit the balls 71 and facilitate the arrangement of the balls in the sets of registering grooves 57 and 68 and 58 and 69. Following the insertion of the balls 71 in the sets of grooves a plug 74 is arranged in each opening 72 15 and a similar plug 75 is arranged in each opening 73. The outer ends of the plugs 74 and 75 are shaped or notched to form flush continuations of the walls of the grooves 68 and 69.

Means is provided for holding the plugs 74 20 and 75 against outward movement and against turning. A longitudinal keyway 76 is provided in the wall of each opening 66 and the plugs 74 and 75 have lugs or keys 77 cooperating with the keyway 76. The keys 77 cooperate with the keyway 76 to hold the plugs against turning and to prevent outward movement or displacement of the plugs so that the upper ends of the plugs remain flush with the walls of the grooves 68 and 69. It is preferred to relate the openings 72 25 and 73 with the lug 70 so that the openings are in the upper portions of the members 63 when the lugs 70 are engaged against the lower ends of the body legs 22. With this relation of parts the plugs 74 and 75 and the adjacent walls of the 30 grooves 68 and 69 are not subjected to the heavy forces transmitted between the cutters 13 and the members 63. The lugs 70 cooperate with the legs 22 for the transmission of forces between the body and the bearing members 63 and if desired 35 may be welded to the legs as illustrated in the drawings.

The bearing members 64 are cylindrical tubular members having central longitudinal openings 78. The members 64 are proportioned to fit the 40 cutter openings 59 with suitable clearance. The outer ends of the members 64 engage against the inner ends of the members 63 and the inner ends of the members 64 cooperate with the end faces of the bosses 62. Each bearing member 64 is 45 provided with an annular ball groove 79 adjacent its outer end and a peripheral annular ball groove 80 at or adjacent its inner end. The members 64 are preferably reduced in external diameter at their inner ends so that their peripheral surfaces 50 join with the bottoms of the grooves 80 as illustrated in Figs. 7 and 9 of the drawings. The grooves 79 oppose or register with the grooves 61 and the grooves 80 oppose or register with the grooves 60. Series of balls 81 occupy or cooperate 55 with the sets of opposing grooves 61 and 79 and 60 and 80. The grooves just mentioned are proportioned so that the balls 81 are effective in supporting the cutters 14 for free rotation and so that the balls constitute the sole cutter supporting elements. The balls 81 in the grooves 61 and 79 are operable to transmit end thrusts in both directions as well as the radial thrusts while the balls 81 in the grooves 60 and 80 are operable to transmit the outward end thrusts as 65 well as the radial thrusts.

In assembling a bearing member 64 in a cutter 14 a row of balls 81 is first arranged in the groove 60 and the member 64 is inserted in the cutter opening 59 and moved to a position where its 70 groove 80 cooperates with said series of balls. A

radial opening 82 is provided in each member 64 and extends from its opening 78 to its groove 79. The openings 82 are provided to admit the balls 81 to the registering grooves 79 and 61. Following the insertion of the balls 81 in these 5 grooves plugs 83 are arranged in the openings 82. The outer ends of the plugs 83 are shaped or notched to form flush continuations of the surfaces of the grooves 79. The plugs 83 are inserted from the inner ends of the openings 82 and 10 means is provided for holding the plugs against turning and outward movement. Keys 84 are provided on the plugs 83 and cooperate with keyways 85 in the walls of the openings 78. The keys 84 cooperating with the keyways 85 serve to 15 retain the plugs 83 in the positions where their outer ends form flush continuations of the walls of the grooves 79.

The supporting member 65 serves to mount or support the bearing members 63 and 64 on the 20 body 10. The web 17 is provided with a transverse or horizontal opening 86. The opening 86 is concentric with and extends through the bosses 62. The lower portions of the legs 22 are provided with openings 87 in longitudinal 25 alignment with the opening 86. The pin or supporting member 65 is passed through the opening 87 in one leg 22, has its intermediate portion supported in the opening 86 and has an end portion threaded in the opening 87 in the other leg 30 22. The opposite end of the supporting member 65 is provided with a head 88 recessed in the outer side of the adjacent body leg 22. The member 65 extends through the openings 66 and 78 of the members 63 and 64, respectively, to 35 support the members and their respective cutters 13 and 14. The member 65 may engage or cooperate with the inner ends of the several plugs 74, 75 and 83 to positively prevent inward movement or displacement of the plugs and to retain their respective keys 77 and 84 in cooperation 40 with the keyways 76 and 85. The support member 65 may be threaded or tightened so that the pairs of bearing members 63 and 64 are clamped together between a body leg 22 and a boss 62 so 45 that there can be no end play in the bearing elements or members.

The inner cutters 13 and 14 rotatably mounted on the body 10 as just described are independently rotatable about a common transverse axis. 50 The cutters 13 project downwardly beyond the lower ends of the legs 22 to act on the bottom wall of the well and the cutters 14 project downwardly beyond the lower end of the web 17 to act on the central portion of the well bottom.

It is believed that the operation of the improved rock bit will be understood from the foregoing detailed description. The body 10 is adapted to be secured to the lower end of a drilling string which is to be rotated in the well 60 bore and fed downwardly in the usual manner. The cutters individually rotate and are supported by the anti-friction ball bearing means to rotate with a minimum of friction. It is to be observed that the outer cutters 11 are each rotatably supported by a single integral bearing member 29. The bearing members 29 are securely held between the body wings 18 and the legs 19. As the members 29 are one-piece and devoid of joints and lines of division there can be no play 65 or working of the parts. Each inner cutter 13 is rotatably supported on a single bearing member 63 through spaced series of balls 71. The members 63 are securely held between the legs 22 and the bearing members 64 and cannot work 70 75

198

2,210,279

5

or play. The cutters 14 are supported on the simple integral bearing members 64 through the medium of the balls 81. The members 64 are securely clamped between the members 63 and 5 the bosses 62.

It is to be particularly noted that the bearing members 29, 63 and 64 are simple and inexpensive to manufacture and to assemble. The several cutters are supported solely by spaced series of balls and it is unnecessary to employ thrust washers or similar parts that are subject to excessive wear. There is a minimum number of parts embodied in the bearing means and the parts are all securely held in place so that they 10 cannot become lost.

Having described only a typical preferred form and application of the invention, I do not wish to be limited or restricted to the specific details herein set forth, but wish to reserve to myself 15 any variations or modifications that may appear to those skilled in the art or fall within the scope of the following claim.

Having described my invention, I claim:

In combination, spaced supports, a boss on one support projecting toward the other, a roller having an opening, a pin extending between the supports and passing through the opening, a 5 tubular bearing member on the pin having two spaced peripheral grooves, one spaced from one end of the member, the other adjacent the other end of the member, the member being reduced in external diameter from its said other end to the 10 said other groove, the member having a radial opening joining the first mentioned groove, balls passed through the radial opening into the said first mentioned groove to rotatably support the roller, balls passed over said other end of the 15 member into the said other groove rotatably supporting the roller, a plug in the radial opening, means holding the plug against movement, and means holding the member where its said other end engages the boss and the boss is received in 20 the roller opening.

ALFRED C. CATLAND.
